William B. Jaspert.

UNITED STATES PATENT OFFICE

WILLIAM B. JASPERT, OF PITTSBURGH, PENNSYLVANIA

TILE FLOOR

Application filed April 2, 1928. Serial No. 266,512.

This invention relates to composite floors and the present invention is an improvement on the invention disclosed in my co-pending application, Serial No. 252,536, filed February 7, 1928, in which I have described a method of supporting a tile by resilient material to deaden the sound of impact from treading on the floor.

In accordance with the present invention, 10 I utilize a fastening strip of sheet metal or other suitable material formed to engage the tile at the lower portion thereof to firmly secure the same on the foundation member, and I further utilize a strip of resilient material which is interlocked with the fastened tile to prevent its accidental removal and to cover up the fastening strip.

In the accompanying drawings constituting a part hereof and in which like reference characters designate like parts, Fig. 1 is a perspective view illustrating a section of a composite floor structure embodying the principles of this invention; Fig. 2 a perspective view of a resilient strip, such as rubber; Fig. 25 3 a similar view of a fastening strip of metal, the strip shown in Figs. 2 and 3 being employed to secure the tile in position; Fig. 4 is a perspective view illustrating a modification of the invention; Fig. 5 a similar view 30 of still a further modification and Fig. 6 a view in perspective of a modified form of the resilient strip or liner utilized between adjacent tile members.

Referring to Figs. 1, 2 and 3 of the drawings, the tile 1 of the general shape as shown in Fig. 1, and having grooves 2 is secured on a foundation member by the fastening strips 3 which are rolled or otherwise formed of sheet metal or other suitable material substantially channel shape as shown in Fig. 3. The strip 3 is provided with flared sides 4 which are adapted to engage the complementary shaped surfaces 5 of the tile 1 in the manner shown in Fig. 1. The strips 3 are secured to the foundation member by nails or screws 6 or in any suitable manner to securely hold the tile in place.

A strip of resilient material such as rubber 7 molded to the general shape of the recess 59 between adjacent tiles, when the latter are

secured in the position shown in Fig. 1, is placed between the tiles and is interlocked therewith.

The structure illustrated in Fig. 1 is assembled in the following manner:—One of 55 the tiles is secured by the strip 3 in the manner shown. The molded resilient strip 7 is then placed in its proper position in a plane overlying the strip 3 and the next adjacent tile is then brought into abutment with the 60 fastening strip 3 and the resilient strip 7 and secured in position by a fastening strip 3 which is placed on the opposite side of the tile in a manner similar to which the strip 65 is secured to the first tile and so on.

In the modification shown in Fig. 4, the tile 1 is rounded at its lower edge 8 to provide a clearance 9 between the fastening strip 3 to prevent abutment of the lowermost edge 70 of the tile with the bottom portion of the fastening strip whereby the flared sides 4 of the strip lie in the grooves 2 and are constituted resilient members adapted to yield under lateral pressure exerted by the tile against the strip. The rubber strip 7 when assembled between the tiles will then be subjected to the lateral pressure exerted by the tile whereby the latter is resiliently held and relatively 75 movable with adjacent tile members. As shown in Fig. 4 and as disclosed in my co-pending application referred to, the tile 1 may be secured on a rubber or felt base 10 so that with the resilient strip 3 and the rubber strip 7 the tile is resiliently mounted on all sides and thus capable of entirely eliminating 80 sound caused by impact with the floor. A tile so secured is furthermore positively held against displacement as is the rubber liner 7 which is interlocked with adjacent tile and the liner 7 need not be fastened in any other 85 manner to prevent its displacement.

In the modification shown in Figs. 5 and 6, the strip 7 is modified to permit the tile to be laid very closely if desired, a narrow spacing strip 11 being provided to prevent actual 95 engagement of adjacent tile members. It is evident that the tile may be laid with a strip of any desired dimension by varying the width of the fastening strips 3 and making the rubber strip 7 to the shape correspond- 100

ing to the spacing between the tile members when they are in their fastened position on the foundation member.

It is evident from the foregoing description of this invention that tiles fastened and mounted in the manner therein described constitute an improved flooring surface which may be produced of ornamental design and color to provide suitable decorative effects.

10 It is also evident that various modifications may be made in the form of the fastening strip and resilient strips and in the shape of the tile and tile edges within the spirit of this invention.

15 I claim herein as my invention:

1. A wearing surface for floors comprising in combination a plurality of tile, means for yieldingly engaging the edges of said tile and for securing the same to a foundation member, and resilient material disposed between adjacent tile and being interlocked with the edges thereof.

2. A wearing surface for floors comprising in combination a plurality of tile, strips of channel shape having flared sides in engagement with the edges of said tile and resilient material disposed between adjacent tile and adapted to cover said strip, said resilient material being interlocked with said tile.

3. A wearing surface for floors comprising in combination a plurality of tile having shoulders formed on the edges thereof, fastening strips for said tile adapted for engagement with the shoulders thereof, and molded rubber strips of preformed shape disposed between adjacent tile and being interlocked therewith.

4. A wearing surface for floors comprising tile having grooves in the edges thereof and having their bottom edges flared, fastening strips for engaging the grooves of the tile and resilient material disposed between adjacent tile and adapted to be locked with the grooves of said tile.

5. A wearing surface for floors comprising tile having grooves in the edges thereof, fastening strips for engaging the grooves of adjacent tile and strips of resilient material disposed between the edges of the tile and projecting into said grooves, said fastening strips being adapted to clear the outer edges of the tile.

6. A wearing surface for floors comprising tile having grooves in the edges thereof, and having their bottom edges rounded, fastening strips for engaging the grooves of adjacent tile, and strips of resilient material disposed between said tile and being interlocked therewith.

7. A wearing surface for floors comprising in combination a plurality of tile having their edges formed of irregular contour, fastening means engaging the edges of the tile to secure them to a foundation member, and

resilient strips formed to the shape of the edges of said tile and adapted for interlocking engagement therewith.

In testimony whereof, I have hereunto set my hand.

WILLIAM B. JASPERT.
